DRYING STRUCTURE

Filed Dec. 22, 1927

21 Inventor
Thomas W. Prosser.

By *Ammon S. Tracy* Attorney

UNITED STATES PATENT OFFICE.

THOMAS W. PROSSER, OF KANKAKEE, ILLINOIS, ASSIGNOR TO PARAMOUNT TEXTILE MACHINERY CO., OF CHICAGO, ILLINOIS, A CORPORATION OF ILLINOIS.

DRYING STRUCTURE.

Application filed December 22, 1927. Serial No. 241,955.

This invention primarily relates to drying structures; it has more especial reference to hosiery drying and shaping devices; and it particularly involves means for separately 5 heating certain components of such devices.

In a companion application, filed on the 5th day of April, 1927, Serial No. 181,215, in the name of myself and Patrick P. La Montagne, there is disclosed a drying and shaping form for "boarding" hosiery and which 10 includes a detachable or interchangeable toe-element, with means for removably mounting the element on the form. The toe-portion of the form and the associated toe-element are 15 provided with intermating faces, with inter-engaging shoulders, and with coacting means for joining the element to the toe-portion to insure and promote adequate heat exchange between the toe-portion and toe-element. 20 These means, in the embodiment disclosed, comprise an elongated recess or slot in one face of the toe-element and a cooperative headed instrumentality outstanding from the corresponding face of the toe-element. 25 The inventive-concept of the present case is a carrying forward of and an adjunct to the structure of that case.

In the present instance, I have provided a holder for temporarily mounting one or more 30 of the toe-elements to accomplish a heating thereof while detached from the forms. This holder is, itself, supported on a conduit which conducts a thermal fluid to the forms, these likewise being mounted on and in communication with the conduit. Thus, both the 35 forms and the holder are under the influence of heat supplied by the heating-medium in the conduit. The holder is provided with means whereby the toe-elements are supported 40 on it in somewhat the same manner that they are on the forms. In consequence, the toe-elements, while on the holder, are subjected to more or less heating so that, when they are transposed to the forms, they possess a 45 certain degree of temperature, such that they are adapted to function to finish hosiery "boarded" on them and their respective forms. In consequence, the toe-elements may be pre-heated before being attached to the forms 50 and are, thus, made ready to perform their function when the forms, themselves, attain the required degree of temperature for "boarding" purposes; or the elements may in this way be kept heated while detached from

the forms and other elements are functioning 55 thereon.

It will now be understood, from the foregoing, that the object of my inventive-concept is to prepare and maintain the detachable toe-elements of drying forms for functioning 60 as drying instrumentalities if and when they are mounted on the forms for a "boarding" operation.

It is also an object within the contemplation of the invention to provide appropriate 65 structure for the purpose specified, and which structure is simple in character, is conveniently disposed in relation to the forms, and is so related thereto that the conduit which supplies a heating-medium to the forms likewise simultaneously supplies heat for heating 70 the detached toe-elements.

While I have herein referred to the instrumentalities which are to be preheated, or kept hot, as "toe-elements", it is to be understood, 75 of course, that my concept contemplates a similar preheating or heating of any other type of detachable or associable component of a drying or "boarding" device; in other words, the concept is not confined to a 80 hosiery-form nor to the toe-element thereof.

In the accompanying drawings—in which I have revealed two embodiments of my concept and one application thereof, and which drawings are to be understood as merely illustrative and the illustrated embodiments of which are susceptible of other embodiments and utilizations and of a wide range of modification and variation without departing 85 from the spirit of the invention or sacrificing any of its salient features or underlying principles—

Figure 1 is a view in front elevation of a hosiery-drying structure constructed in accordance with one of the embodiments of my 90 invention, parts being broken away more clearly to reveal certain features thereof;

Fig. 2 is an enlarged view, in vertical section, on the line 2—2, Fig. 1;

Fig. 3 is a view in perspective of the element-sustaining holder forming an adjunct 100 of the structure;

Fig. 4 is a view in elevation of one of the toe-elements, detached; and

Figs. 5 and 6 are views in sectional elevation 105 and vertical cross-section of a modified type of holder.

In these drawings, the reference-character

1 designates a table of the general type and construction shown in United States Letters Patent No. 1,610,098, dated December 7, 1926, of Patrick P. LaMontagne, and to which reference is hereby made for details of construction. These details constitute no part of my present concept; hence, I do not deem it essential to describe them at length.

Extending longitudinally of the table is a conduit 2, connected to a suitable source (in this instance) of steam-supply (not shown) for conducting a thermal fluid, or the like. This conduit involves a system comprising, in this instance, a series of pipes 3 and 4, respectively, a control-device 5, a supply-pipe 6, a steam-trap 7, and a water-leg 8, such as are disclosed in my companion application Serial No. 43,216, filed July 13, 1925, entitled "Drying apparatus."

20 On the pipe 4, and upstanding from the table 1, is a series of drying-forms 9, each hollow to contain a heating-medium and having an air-pipe 10 within it and communicating with the pipe 3, and having, also, a detachable toe-element 11, all as disclosed in the aforementioned application Serial No. 181,215.

As therein explained, each toe-element 11 is provided with a flat form-engaging face 12, 30 a transversely extending shoulder 13, and an elongated, undercut slot 14, these features cooperating with a corresponding face 15 on the toe-portion of the form, a shoulder 16 thereon, and a headed instrumentality 18 outwardly standing from that face.

To provide for the "boarding" of various sized stockings, the toe-elements are of relatively different sizes: For instance, that marked 11^a may be size 9, another, 11^b, may 40 then, be size 10, and so on throughout the series. Each toe-element, whatever its size, is adapted to interfit on any of the series of the forms on the table; hence, any of these forms may readily be converted from size 9, for instance, to size 10, by interchanging the toe-elements thereon.

By reason of the fact that the thermal fluid in the form does not always quickly transmit its heat (when first started up) from the form to the toe-element thereon, I have conceived the desirability of preheating the elements and, likewise, to keep them heated while not in use, on the forms. To that end, I have devised a holder 19 for temporarily 55 mounting the elements so that their temperature may be maintained at a predetermined degree and suitable, in many instances, for immediate boarding action when attached to the forms.

60 This holder or support 19 is mounted on the conduit 2—in this instance, on the pipe 6 of the conduit—so that it is subject to the heat transmitted from the conduit and which heat the holder in turn imparts to the elements mounted thereon. Thus, it is seen that

both the series of forms and the holder are mounted on a conduit which is common to them.

Preferably and as shown, the holder comprises two companion members 20, each of these being an elongated plate and having a substantially flat heat-imparting face 21 of considerable area. The opposite side of each plate is formed with an elongated control groove 22 and two arcuate grooves 23 above and below the groove 22. When the members are in mating relation, the grooves 22 form a substantially round bore through which the conduit 6 extends, as shown. The upper edges 24 of the upper groove 23 constitute ledges upon which, when a toe-element 11 is mounted on the holder, its shoulder 13 rests.

As shown in Fig. 3, the holder is so constructed and disposed as to mount two series of the elements 11, one series on each plate or 85 member 21.

Preferably and as shown, means are provided on the element-engaging faces of the holder for receiving and interfitting with the slots 14 of the elements. These means, in this instance, involve headed instrumentalities 25 outstanding from the holder-faces and corresponding, in size, form and construction (generally) to the headed instrumentalities 18 on the toe-portion, which also interfit with the toe-element when it is mounted on the form.

To attach the holder-members together and about the conduit, means are provided, these being (in this instance) screws 26 extending through the plates 20, as clearly shown in Fig. 2. As thus constructed, the holder or support 19 constitutes, as an article of manufacture, a device adapted to encompass the supply conduit 6; it is adapted to support, on each of its sides, a series of toe-elements; and it is heated and maintained more or less hot by the thermal medium flowing through the conduit 6 and which also flows through the supply conduit 3 and thence into the forms 9, so that both the forms and the holder are heated and maintained relatively hot while the forms 9 are being heated and while hot.

I have thus provided means, conveniently located to the forms, for temporarily mounting one or more of the detachable toe-elements 11 so that they may be effectively heated simultaneously with the heating of the forms 9 and the toe-elements which may then be on the forms. In consequence, this structure provides means for effecting a heating simultaneously of the toe-element which may then be on the form and, also, the toe-elements which may then temporarily be on the holder 19. The heated instrumentalities 25 present a simple form of attaching device for mounting the toe-elements on the holder, while the broad faces 21 of the companion members 20 present a substantial heating surface to the contacting faces 12 of each of the toe-ele-

ments. The intimate engagement of the holder 19 with the conduit 6 and, then, the close engagement or contact of the elements 11 with the holder 19 insure rapid heating 5 of the elements and also a desirable maintenance of heat therein while on the holder awaiting their being mounted on the forms.

In Figs. 5 and 6, a somewhat different type 10 of element holder is shown. In this instance, the holder, designated generally by the reference-character 27, is a one-piece device, hollow to provide a longitudinal chamber 28. In this instance, the conduit 6, instead of extending entirely through the holder, has portions 6^a threaded into the ends of the holder so that the conduit, itself, is in fluid communication with the chamber 28. The holder is provided with upper and lower longitudinal grooves 29, these providing oppositely disposed ledges 30 on which the toe-elements 11 are to be seated, as already described in conjunction with the manner of mounting the toe-elements 11 on the holder 19. Outstanding from the opposite sides of the holder 25 27 are headed instrumentalities 31 similar to the elements 25 on the holder 19. This type of holder may, in some instances, have practical advantages over the one previously described, in that, in the first place, it comprises a single casting, and, in the second place, the chamber 28 permits the thermal fluid to have a more direct action on the holder to heat it than may be possible in the type of holder 19, where the heat of the thermal fluid is first effective on the walls of the conduit 6 and these, in turn, impart heat to the members 21 of the holder.

In practical use of this structure, it has 40 been found to be quite efficient for the purpose designed: it is of such a structural character as to be readily embodied in the regular equipment of the boarding table 1; and it materially speeds up production in a plant because, as the toe-element becomes almost as 45 hot on the holder as when heated on the forms, the operator may start boarding on the forms with the interchanged toe-element immediately after the replacement has been effected. Besides, the toe-elements are always ready for use whenever the requirements 50 of the boarding operation necessitate an interchange of these elements on the forms. In addition, where an extra set or series of the toe-elements is at hand, the

holder provides a means for storing them in 55 a systematic way so that the correct sizes may be selected readily when interchanging the toe-elements. Furthermore, the elements are, in this way, stored in a way that will preclude their becoming nicked or otherwise 60 damaged when not in use. Another decided advantage in keeping the toe-elements hot when not in use is that this prevents tarnishing of the nickel plated iron or aluminum elements because it keeps them dry. 65

What I claim is:

1. A drying structure including, in combinative association, a conduit for supplying a heating medium to a series of drying forms, an element-holder on the conduit for sustaining a series of toe-elements positionable on the forms; said holder comprising companion members encompassing the conduit; and element-attaching instrumentalities on the holder for detachably supporting the elements. 70

2. A hosiery-drying structure including, in combinative association, a toe-element for a drying-form having a shoulder on one of its faces; a support for the element and comprising an element-sustaining member having an upstanding portion upon which the shoulder of the element rests while its face is in substantial parallelism with the outer face of the member. 80

3. A hosiery-drying structure including, in combinative association, a series of detachable toe-elements, each formed with a shoudered face and a slot; and an element-holding device comprising companion members, each having an upstanding element-engaging portion; means for connecting the members together; a conduit extending between and encompassed by the members; and outstanding instrumentalities on each member for detachably supporting a series of the toe-elements for simultaneous heating by heat transmitted from a thermal medium in the conduit. 95

4. As an article of manufacture, a holder for hosiery-drying toe-elements including 100 companion members formed with a central pipe-encompassing bore, oppositely disposed element-engaging shoulders thereon, outstanding element-supporting instrumentalities, and means for holding the companion members together. 105

In testimony whereof I affix my signature.
THOMAS W. PROSSER.
